UNITED STATES PATENT OFFICE.

THOMAS DE LA MARE, OF TOOKE, UTAH, ASSIGNOR TO ARTHUR V. SMITH, OF MAMMOTH, UTAH.

PROCESS FOR PRESERVING WOOD.

Application filed April 17, 1925. Serial No. 23,842.

My invention relates to wood preservation, and has for its object to provide a new process for preserving the portions of poles, posts, railway ties and other wood which are buried in the ground and subject to rotting.

These objects I accomplish with the present process which consists of surrounding the pole or other wood with creosote, metal, asphalt and concrete, and saturating the 10 wood thus surrounded with brine, and adding to the brine from time to time in order that capillary attraction will raise the brine above its normal level.

In order that the process may be economically and successfully carried out, I provide an apparatus by which I apply the different steps of my process. As shown in the drawings to illustrate my process and the apparatus by which it is carried out, Figure 1 is a 20 vertical diametrical section of the lower end of a pole with my apparatus thereon for carrying out my process. Figure 2 is an elevation of a reinforcement casing. Figure 3 is a plan view of one form of the apparatus. Figure 4 is a horizontal section of the reinforcement casing shown in Figure 2. Figure 5 is a view in perspective of the apparatus used when my process is applied to preserving railway ties. Figure 6 is a transverse 30 section through the medial portion of the railway tie when the process is applied thereon; and Figure 7 is an elevation of the end of the same tie.

Some of the elements used by me in my process have been known and used as wood preservatives, but not in the way I use them, and the application has not been continued or repeated and never, so far as known to me, have the different steps been used. I 40 will describe my process as applied to preserving telegraph or telephone poles as it will be obvious that the process may be used to preserve any wood which is partially buried in the ground, whatever form it may 45 have or the use to which it is put.

In preserving a telephone pole A, a hole is centrally bored therein from the end to be placed in the ground and extending upwardly to near the surface of the ground, and 50 opening into said hole is another hole B inclined upwardly and extending to the surface of the pole. A pipe or short tube C has one end inserted within said hole B and the other end portion extends further up the pole and preferably parallel therewith. A

cylindrical metal casing D, somewhat larger than the pole, is concentrically spaced around the lower portion of the pole, and, in order that it will not interfere with the dipping of the lower end portion of the pole in 60 creosote, said casing is made detachable by cutting the sheet metal out of which the said casing is made into strips or quarters of the circumference and forming radially extended flanges 1 on both side edges of each strip, 65 which flanges are fastened together by bolts and nuts 2.

My process consists of filling hole A with salt; then covering the exterior of said pole with creosote and placing the pole in a hole 70 dug in the ground larger than the pole; then placing the said casing D around the lower portion of the pole and placing the said pipe C within the said casing D and its lower end within the upper end of said hole B, 75 and filling the interior of said casing D with plastic asphalt E. Then one or more reinforcing wires 3 are passed through holes in the upper end of the flanges 1 of said casing D and plastic cement concrete F is poured 80 around said casing D and filling the hole in the ground. The upper edge of the concrete is tapered upwardly and toward the asphalt. Brine is to be poured from time to time within the said tube C to dissolve the 85 salt in the said hole A, and capillary attraction will cause the brine to raise and fill the ports of the wood and preserve all of the pole from decay up to and above the top of the asphalt.

In preserving railway ties, the process is the same but the apparatus by which it may be carried out is changed in form, as shown in Figures 5, 6 and 7. A longitudinal recess J is provided on the lower side face of a 95 railway tie by two narrow strips of wood 4, which are longitudinally nailed to the bottom of said tie near the lower corners, and a flat board 8 is nailed to said strips and tie by nails passing through both the board and strips. A hole 6 is bored laterally through the said tie and opening into said recess J. A sheet metal casing or box 5 is made larger than the tie and the recess forming members, and is to be spaced from the bottom and 100 sides of said tie by a layer of plastic material, such as asphalt. In using my process for preserving a railway tie, the said recess J is filled with salt and the tie is 105 placed in the box 5, which has recesses 7 cut 110

therein to receive the rails R, which are to rest on the tie. The space between the inside of the said box 5 and below and on the sides of the tie is then filled with plastic asphalt and the upper edges of the box are bent downwardly over the upper side of the tie, and a space surrounding the box 5 is then poured full of cement concrete; then, with brine poured into said hole, the pores of the tie will be filled with brine and the tie will be preserved.

Having thus described my invention I desire to secure by Letters Patent and claim:—

1. A process for preserving wood partially buried in the ground which consists of providing an opening in said wood extending from the bottom upwardly to near the

surface of the ground; filling said opening with salt; surrounding said wood with a layer of plastic asphalt; surrounding said asphalt with cement concrete and filling said opening with brine.

2. A process for preserving the portion of wood which is buried in the ground which consists of providing an opening in the bottom of said wood to the surface of the ground; and partially filling said opening with salt; and filling said opening and the voids of the salt with brine poured from above the ground.

In testimony whereof I have affixed my signature.

THOMAS DE LA MARE.
